UNITED STATES PATENT OFFICE.

GUSTAVE A. ZUNDEL, OF NEW YORK, N. Y.

KEY-FRAME.

SPECIFICATION forming part of Letters Patent No. 770,549, dated September 20, 1904.

Application filed March 18, 1903. Serial No. 148,292. (No model.)

To all whom it may concern:

Be it known that I, GUSTAVE A. ZUNDEL, a citizen of the United States, residing in New York, borough of Manhattan, and State of New York, have invented certain new and useful improvements in Key-Frames, of which the following is a specification.

The object of this invention is to provide a cheap and durable supporting-frame for a Morse key. These keys have been hitherto mounted upon frames provided with adjustable screws forming bearings for the bearing-points of the key-arbor.

The object of this invention is to provide a bearing for said arbor which does not require the employment of these bearing-screws, such a frame being especially desirable for the cheaper grades of instruments, such as learners' sets.

For this purpose the invention consists of a key-frame comprising a base portion and bearing-standards rising one at each side of said base and provided each at its upper portion with an entrance-slot for the journal or bearing portion of the key-lever and at the inner portion of said entrance-slot with an upwardly-extending bearing-socket adapted to receive said journals.

The invention consists, further, in certain details of construction and combinations of parts, which will be fully described herein-after and finally pointed out in the claims.

In the accompanying drawings, Figure 1 is a perspective view of a telegraph-key provided with my improved key-frame. Fig. 2 is a plan view of the sheet-metal blank from which the key is formed. Fig. 3 is a plan view of the completed key-frame, and Fig. 4 is a vertical longitudinal section on line 4, 4-4, Fig. 3.

Similar letters of reference indicate corresponding parts.

Referring to the drawing, A indicates the blank of my improved key-frame. Said blank is formed from sheet metal—such, for example, as sheet-iron of approximately one-sixteenth of an inch in thickness. It is shaped by being stamped, sawed, or otherwise cut from the sheet. Said blank consists of a body portion *a* and two oppositely-located

arms *a'*, one at each side of said body portion extending laterally therefrom in opposite directions. Each is provided with a recess or slot *a''*, extending transversely from the forward edge of the arm inwardly (rearwardly) 55 to approximately the middle of the same. At their inner ends or portions said recesses *a''* merge into sockets *a'''*, located at the outer side of said recesses *a''*—i. e., at that side of the same toward the ends of said arms *a'* and removed from the body portion *a*. At its forward portion said body portion of the blank is provided with two openings *a⁴* *a⁵*, arranged approximately on the longitudinal center line 60 of the same. At its rear portion said body portion *a* is provided with a threaded opening *a⁶*, also arranged approximately on the longitudinal center line of the body portion *a*. At its left side—i. e., at the left hand side of the center line of said body portion—is arranged 65 in the body portion an opening *a⁷*.

For forming the key-frame from said blank the laterally-extending arms *a'* are bent in upward direction, so as to stand approximately parallel and vertical. By this operation 75 the sockets *a'''* are brought into position at the upper sides of the recesses *a''*, the recesses and sockets of one standard being located opposite those of the other standards. Said key-frame is secured to the base *B* of the 80 telegraph instrument by means of a screw *b*, passing upward through said base and engaging in the threaded opening *a⁶*. It is also secured by a screw which passes upwardly through the opening *a⁷* and which forms also 85 the pivot for the switch-lever *b²* and by a screw passing in upward direction through the base *B*, opening *a⁴*, and insulating-washer *b⁴* and into the contact *b⁵*. C indicates the key-lever, which is provided with laterally-extending journals or bearing portions *c*, 90 adapted to enter the recesses *a''* of the bearing-standards *a'* of the key-frame and to be seated in the sockets *a'''* of said bearing-standards. *c'* indicates a key-spring which is arranged beneath the lever at the forward side of the bearings *c*. Said spring *c'* is a coil-spring and is located at its lower portion in the opening *a⁵* of the base *a* of the key-frame. It rests upon the base *B* of the instrument. 100

At its upper end it bears against the under side of the key-lever C between the bearings c and the key-grip d. c² indicates an adjusting-screw at the rear of the key, said screw bearing at its lower end upon the rear portion of the base a of the key-frame. By this construction the spring maintains the journals c of the key-lever constantly in raised position yieldingly in the sockets a³. The entire key is thereby retained in proper position.

It is obvious that the entrance-recesses a² may be inclined instead of horizontal, as shown in the drawings. That portion of each standard adjacent and below the bearing-socket of the same forms a guide, aiding in the insertion of the journal into the bearing-socket. It also forms an abutment which, being located adjacent and opposite the open side of the socket, serves for preventing ready dislodgment of the journal.

Having thus described my invention, I claim as new and desire to secure by Letters Patent—

1. The combination of a sheet-metal key-frame, comprising a base and standards, said standards each provided with a recess extend-

ing horizontally into the same from the edge thereof, a bearing-socket in each standard communicating with said recess, a key having journals adapted to enter said recesses and sockets, and means retaining said journals 30 yieldingly therein, substantially as set forth.

2. The combination of a key-frame, comprising two standards, a bearing-socket in one standard, a bearing-socket in the other standard, a recess extending horizontally into the 35 latter standard and communicating with said bearing-socket of the same, a key having a journal adapted to enter said first socket, and a journal adapted to enter said recess and socket, and means retaining said journals 40 yieldingly in said sockets, substantially as set forth.

In testimony that I claim the foregoing as my invention I have signed my name in presence of two subscribing witnesses.

GUSTAVE A. ZUNDEL.
